SLUG CASTING MACHINE

John H. Hilpman, Springfield Gardens, N. Y., assignor to Mergenthaler Linotype Company, a corporation of New York

Application September 3, 1936, Serial No. 99,193

20 Claims. (Cl. 199—49)

This invention relates to slug casting machines of the general organization represented in U. S. Letters Patent to O. Mergenthaler, No. 436,532, wherein circulating matrices and expansible spacebands are released from their respective storage magazines and then assembled in line, the composed line transferred to a vertically movable transporter or first elevator which thereupon descends to present it to the face of a slotted mold, the spacebands then expanded to justify the line and the mold filled with molten metal to cast a type-bar or slug against the line, and the transporter thereafter raised to its uppermost level and the matrices and spacebands returned through transfer and distributing mechanism to the magazines from which they started.

The matrices employed in these machines are formed on their opposite edges with upper and lower projecting ears and are usually provided on their casting edges with two superposed characters, one roman and the other italic or otherwise. In composing a line including both kinds of characters, the matrices are assembled at two different levels, and when the line is transferred to the line transporter, those matrices standing at the lower level (with their upper or roman characters in casting position) are supported therein by their upper ears which rest on a pair of fixed rails formed on the inner walls of the front and rear jaws of the transporter, while those matrices standing at the upper level (with their lower or italic characters in casting position) are supported in the transporter solely by their lower front ears which rest on a single retractile rail arranged in the front jaw of the transporter.

In practise it has been found that the matrices standing in the transporter at the upper level (due to the fact that they are supported solely by their lower front ears) frequently become turned or twisted and fall out of the transporter or else become so badly displaced as to cause damage to themselves and other parts of the machine (as during casting) or to interfere with the normal operation of the machine (as during line transfer). This objectionable twisting or displacement occurs particularly during the ascent of the transporter following a casting operation, at which time the matrices may lack lateral support, e. g. after a quadding or centering operation or after the return of the spacebands to unexpanded condition. The occurrence is most frequent during recasting, i. e. when the same line of matrices is used repeatedly to produce duplicate slugs, and when of course the

transporter is required to present the line in casting position more than once before the line is removed therefrom.

The present invention is intended to obviate the above and other difficulties and, to this end specifically, the transporter is equipped with friction members, in the form of thin flat downwardly-bowed springs, arranged on its front and rear jaws in position to bear upon the top edges of the upper projecting ears of those matrices supported therein at the upper level. These springs not only serve by their friction effect to retain the matrices in proper place upon their supporting rail but in addition they assist, by the downward pressure which they exert, in bringing the matrices to the lower level (in alignment with those already supported at that level) when their supporting rail is automatically retracted preparatory to the transfer of the line from the transporter.

In the accompanying drawings, the invention has been shown merely by way of example and in preferred form and obviously many changes and variations may be made therein and in its mode of application which will still be comprised within its spirit. It is to be understood, therefore, that the invention is not limited to any specific form or embodiment except insofar as such limitations are specified in the appended claims.

In the drawings:—

Fig. 1 is a front elevation, partly broken away, of a portion of a slug casting machine embodying the present improvements, and showing certain parts of the line assembling, line delivery, and line transfer devices;

Fig. 2 is a front elevation of the rear jaw of the line transporter showing the matrix engaging spring in its normal inactive position and showing a composed line of matrices in the course of transfer into the transporter;

Fig. 3 is a similar view, showing the composed line (with matrices standing at different levels) after it has entered the transporter, and showing the spring as it appears in action;

Fig. 4 is a top plan view of the transporter, and showing the springs as attached to both its front and rear jaws;

Fig. 5 is an end view of the transporter shown as containing a line of matrices;

Fig. 6 is an exploded view of the rear jaw of the transporter, its matrix engaging spring and attaching parts; and

Fig. 7 is a vertical section through the rear transporter jaw, taken on the line 1—1 of Fig. 2,

and showing the matrix engaging spring in its normal position.

In the operation of the machine, the matrices 10 and spacebands 11 are delivered from their places of storage by the manipulation of the keyboard (not shown) and are composed in line in the assembling elevator 12. After the line has been composed, the assembling elevator 12 is raised to position it between the depending fingers 13 and 14 of the line delivery slide 15, which thereupon transfers the line through the intermediate channel 16 into the vertically movable line transporter or first elevator 17. The line transporter 17 then descends to casting position, where the composed line is located in front of the mold and between the vise jaws 18 and 19 which clamp the line endwise during the slug casting operation. Before the line is completely clamped up, however, justification of the line takes place, the spacebands being expanded to move the matrices apart and spread the line to full length. After the slug is cast, the pressure on the vise jaws 18 and 19 is released and the line transporter 17 ascends to its upper transfer position, as shown by the dotted lines in Fig. 1, where the transfer slide 20 removes the line from the transporter 17 into the upper transfer channel 21 from which the matrices 10 and the spacebands 11 are returned to their usual places of storage.

30 As usual, each of the matrices 10 is formed on its opposite edges with upper and lower projecting ears 22 and 23, respectively, and on its rear or casting edge with two superposed characters 25 and 26, one roman and the other italic or otherwise. At the top, the matrix is provided with the customary tooth combination web 24.

When a printing slug bearing both kinds of characters is to be cast, the matrices are composed at two different levels in the assembling 40 elevator 12 so as to bring their upper and lower characters, as selected, into horizontal alignment, the matrices being maintained at the different levels during the line delivery and casting operations and until just prior to the transfer of the 45 line from the transporter.

The transporter 17 comprises front and rear jaws 27 and 28 formed with a pair of upper fixed rails 29 and 30 (Fig. 5) arranged to support matrices standing at the lower level by their upper 50 projecting ears 22. The front jaw 27 is also provided with a lower retractile rail 31 arranged to support matrices standing at the upper level by their front lower ears 23 only, the rail being automatically retracted when the transporter is in the upper transfer position by depending overhead projections 32 on the machine frame to allow the matrices at the upper level to drop to the lower level prior to the transfer of the line from the transporter. Matrices that fail to drop by 60 gravity to the lower level as the rail 31 is retracted are pushed down by a stationary V-shaped bar 33 positioned to engage the tooth combination webs 24 of the matrices.

65 The spacebands 11 are supported in the transporter in the usual way, being formed at the top and at opposite edges with narrow ears 11a which enter correspondingly narrow grooves 11b formed in the opposed faces of the transporter jaws 27 and 28.

70 Inasmuch as those matrices which are assembled at the upper lever are supported in the line transporter 17 only by their front lower projecting ears 23 which rest on the retractile rail 75 31, they frequently become twisted or turned or

otherwise displaced during the movement of the transporter 17, and give rise to the objections before mentioned.

The means provided by the present invention to prevent such occurrence, in the specific embodiment illustrated, comprise two flat springs 34 and 35 secured to the front and rear jaws of the transporter just above the spaceband grooves 11b and beneath shoulders 36 and 37, respectively, these springs being made with a permanent downward bow (see Figs. 2 and 5) and arranged to bear upon the top edges of both upper ears 22 of matrices supported in the transporter at the upper level. Each spring is formed with a pair of upwardly extending lugs 38, one near each end, fitting into vertical recesses 39 cut in the inner walls of the transporter jaws and secured therein by means of tap bolts or studs 40, the unthreaded or shank portions of the studs passing through holes 41 drilled through the jaws of the transporter and through apertures 42 in the lugs, and the threaded or end portions of the studs being screwed into tapped holes 43 in retaining plates 44 channeled or recessed to fit over the lugs.

At the line receiving end of the transporter, the 25 springs are bent upwardly against shoulders 45, formed by cutting away the jaws of the transporter, so as not to interfere with the entrance of the matrices into the transporter; and to prevent edgewise displacement of the bent up ends, they 30 are protected by outwardly extending guard plates 46 formed on the adjacent retaining plates 44.

In order to permit the downwardly-bowed springs to straighten out and adjust themselves 35 to the matrices as the latter enter the transporter, the attaching lugs 38 are permitted a certain amount of play, this being provided for by slightly widening the recesses 39 in the transporter jaws, as well as the recesses in the retaining plates 44, and by slightly enlarging the apertures 42 in the lugs (see Fig. 3). As the springs are straightened out, they will, of course, exert a downward pressure on the matrices, but in this connection it should be noted that the 45 springs are so thin and flexible as to accommodate themselves to any irregularities in alignment of the top edges of the matrices, due to wear or other causes.

With this arrangement, when a composed line 50 with matrices assembled at both levels is delivered into the transporter 17, the yieldable springs 35 frictionally engage and exert downward pressure on the top edges of the upper projecting ears 22 of the matrices supported at the upper level and hold the matrices in proper place upon the retractile supporting rail 31, overcoming any tendency of the matrices to turn or twist. In addition, when the rail 31 is retracted to allow the matrices at the upper level to drop to the lower level, the springs impart a slight downward impetus to the matrices and act, particularly on the thinner light-weight matrices, to dislodge any which tend to stick sufficiently so as not to drop by gravity, thereby lessening the frequency with which matrices strike the stationary V-shaped bar 33 during the ascent of the transporter with consequent damage to the delicate teeth of the combination webs 24.

Various alternative arrangements will readily suggest themselves to those skilled in the art. Thus, some of the benefits of the invention could be realized by substituting for the springs 35 solid steel plates urged downwardly by springs 75

or by gravity to frictionally engage the upper ends of the matrices standing at the upper level. Likewise, stationary plates with soft or yielding matrix engaging surfaces might be used to advantage. Such modifications and others of similar character obviously would come within the scope of the present invention as defined in the appended claims.

Having thus described my invention, what I claim is:

1. In or for a slug casting machine, a line transporter provided with means for supporting matrices at upper and lower levels therein and with means to frictionally engage from above the top edges of matrices standing at the upper level.

2. In or for a slug casting machine, a line transporter provided with means for supporting matrices at upper and lower levels therein and with means to frictionally engage the top edges of matrices standing at the upper level, said friction means presenting a yieldable matrix engaging surface capable of conforming to irregularities in alignment of the top edges of the matrices.

3. In or for a slug casting machine, a line transporter provided with means for supporting matrices at upper and lower levels therein and with a friction member arranged to engage from above, at one side of the composed line, the top edges of matrices supported at the upper level.

4. In or for a slug casting machine, a line transporter provided with means for supporting matrices at upper and lower levels therein and with a pair of friction members arranged to engage, at both sides of the composed line, the top edges of matrices supported at the upper level.

5. A line transporter as specified in claim 1, characterized by the fact that the friction means therein referred to are in the form of long springs overlying the upper level matrices.

6. A line transporter as specified in claim 1, characterized by the fact that the friction means therein referred to are in the form of long downwardly-bowed springs overlying the upper level matrices and loosely mounted at their opposite ends to permit straightening when engaged by the matrices.

7. A line transporter as specified in claim 1, characterized by the fact that the friction means therein referred to are in the form of long springs overlying the upper level matrices and so thin and flexible as to conform to irregularities in alignment of the top edges of the matrices.

8. In or for a slug casting machine equipped with matrices formed on their front and rear edges with upper and lower projecting ears, a line transporter comprising front and rear jaws formed with an upper pair of fixed rails to support matrices by their two upper projecting ears at a lower level and the front jaw having a lower rail to support matrices by their lower front projecting ears at an upper level, said transporter being provided with a friction member arranged to engage from above, at one side of the composed line, the top edges of the upper projecting ears of matrices supported at the upper level.

9. In or for a slug casting machine equipped with matrices formed on their front and rear edges with upper and lower projecting ears, a line transporter comprising front and rear jaws formed with an upper pair of fixed rails to support matrices by their two upper projecting ears at a lower level and the front jaw having a lower

ears at a lower level and the front jaw having a lower rail to support matrices by their lower front projecting ears at an upper level, said transporter being provided with a pair of friction members arranged to engage, at opposite sides of the composed line, the top edges of the upper projecting ears of matrices supported at the upper level.

10. In or for a slug casting machine equipped with matrices formed on their front and rear edges with upper and lower projecting ears, a line transporter comprising front and rear jaws formed with an upper pair of fixed rails to support matrices by their two upper projecting ears at a lower level and the front jaw having a lower rail to support matrices by their lower front projecting ears at an upper level, said transporter being provided with a long flat spring arranged to bear down, at one side of the composed line, upon the top edges of the upper projecting ears of matrices supported at the upper level.

11. In or for a slug casting machine equipped with matrices formed on their front and rear edges with upper and lower projecting ears, a line transporter comprising front and rear jaws formed with an upper pair of fixed rails to support matrices by their two upper projecting ears at a lower level and the front jaw having a lower rail to support matrices by their lower front projecting ears at an upper level, said transporter being provided with a pair of long flat springs arranged to bear down, at opposite sides of the composed line, upon the top edges of the upper projecting ears of matrices supported at the upper level.

12. In or for a slug casting machine equipped with matrices formed on their front and rear edges with upper and lower projecting ears, a line transporter comprising front and rear jaws formed with an upper pair of fixed rails to support matrices by their two upper projecting ears at a lower level and the front jaw having a lower rail to support matrices by their lower front projecting ears at an upper level, said transporter being provided with a long flat spring arranged to bear down, at one side of the composed line, upon the top edges of the upper projecting ears of matrices supported at the upper level, said spring being thin and flexible enough to conform to irregularities in alignment of the top edges of the matrix projecting ears.

13. In or for a slug casting machine equipped with matrices formed on their front and rear edges with upper and lower projecting ears, a line transporter comprising front and rear jaws formed with an upper pair of fixed rails to support matrices by their two upper projecting ears at a lower level and the front jaw having a lower rail to support matrices by their lower front projecting ears at an upper level, said transporter being provided with a long flat spring arranged to bear down, at one side of the composed line, upon the top edges of the upper projecting ears of matrices supported at the upper level, said spring being made with a permanent downward bow and loosely mounted at its opposite ends to permit straightening when engaged by the matrices.

14. In or for a slug casting machine equipped with matrices formed on their front and rear edges with upper and lower projecting ears, a line transporter comprising front and rear jaws formed with an upper pair of fixed rails to support matrices by their two upper projecting ears at a lower level and the front jaw having a lower

5 rail to support matrices by their lower front projecting ears at an upper level, said transporter being provided with a long flat spring arranged to bear down, at one side of the composed line, upon the top edges of the upper projecting ears of matrices supported at the upper level, said 10 spring being formed at the receiving end of the transporter with an upwardly turned portion to avoid interference with the matrices as they enter the transporter.

15 15. In or for a slug casting machine equipped with matrices formed on their front and rear edges with upper and lower projecting ears, a line transporter comprising front and rear jaws formed with an upper pair of fixed rails to support matrices by their two upper projecting ears at a lower level and the front jaw having a lower rail to support matrices by their lower front projecting ears at an upper level, said transporter 20 being provided with a long flat spring arranged to bear down, at one side of the composed line, upon the top edges of the upper projecting ears of matrices supported at the upper level, said 25 spring being backed up by a correspondingly long overlying shoulder formed on the transporter.

30 16. In or for a slug casting machine equipped with matrices formed on their front and rear edges with upper and lower projecting ears, a line transporter comprising front and rear jaws formed with an upper pair of fixed rails to support matrices by their two upper projecting ears at a lower level and the front jaw having a lower rail to support matrices by their lower front projecting ears at an upper level, said transporter 35 being provided with a long flat spring arranged to bear down, at one side of the composed line, upon the top edges of the upper projecting ears of matrices supported at the upper level, said 40 spring being formed at the receiving end of the transporter with an upwardly turned portion to

avoid interference with the matrices as they enter the transporter and backed up by a corresponding shoulder formed on the transporter.

17. A transporter as specified in claim 10, characterized by the fact that the rail for supporting the matrices at the upper level is retractible and that the overhead spring acts to depress such matrices to the lower level when the rail is retracted.

18. In or for a slug casting machine, a line 10 transporter provided with means for supporting matrices at upper and lower levels therein and with a friction member arranged to cooperate solely with the upper level matrices and hold them in proper place upon their supporting 15 means.

19. In or for a slug casting machine, a line transporter movable to and from casting position and provided with means for supporting matrices at upper and lower levels therein, said 20 transporter being also provided with a pair of friction members arranged to engage the upper level matrices at opposite sides of the composed line.

20. In or for a slug casting machine equipped 25 with matrices formed on their front and rear edges with upper and lower projecting ears, a line transporter movable to and from casting position and comprising front and rear jaws, said jaws being formed with an upper pair of fixed 30 rails to support matrices by their two upper projecting ears at a lower level and the front jaw having a lower rail to support matrices by their lower front projecting ears at an upper level, said transporter 35 being provided with a friction member arranged on the rear jaw of the transporter in position to engage with the upper level matrices and serving to hold them in proper place upon their single front supporting rail.

JOHN H. HILPMAN. 40
